CLAIM

The ornamental design for a spill container for above ground storage tanks, as shown and described.

DESCRIPTION

FIG. 1 is a perspective view of a spill container for above ground storage tanks showing my new design with the access door closed;

FIG. 2 is a front view thereof;

FIG. 3 is a rear view thereof;

FIG. 4 is a side view thereof;

FIG. 5 is a top view thereof;

FIG. 6 is a bottom view thereof;

FIG. 7 is a front view thereof with the access door open; and,

FIG. 8 is a side view thereof with the access door open.

The broken line showing is for illustrative purposes only and

forms no part of the claimed design.
